(57) **CLAIM**

We claim the ornamental design for a garment hanger, as shown and described.

DESCRIPTION

FIG. 1 is a front view of a garment hanger showing our new design;

FIG. 2 is a rear view thereof;

FIG. 3 is a top view thereof;

FIG. 4 is a bottom view thereof;

FIG. 5 is a left view thereof; and,

FIG. 6 is a right view thereof.

The broken lines shown represent unclaimed subject matter and form no part of the claimed design.
